US00D981046S

(12) **United States Design Patent** (10) **Patent No.:** **US D981,046 S**
(45) **Date of Patent:** **** Mar. 14, 2023**

(54) **ELECTRIC DRY SHAVER HEAD**

(71) Applicant: **Braun GmbH**, Kronberg (DE)

(72) Inventors: **Philipp Goeder**, Frankfurt (DE);
Gregor Ptak, Frankfurt (DE);
Bernhard Sikora, Kelkheim (DE);
Wolfgang Stegmann, Frankfurt (DE)

(73) Assignee: **Braun GmbH**, Kronberg (DE)

(**) Term: **15 Years**

(21) Appl. No.: **29/781,624**

(22) Filed: **Apr. 30, 2021**

Related U.S. Application Data

(62) Division of application No. 29/709,111, filed on Oct. 11, 2019, now Pat. No. Des. 921,985, which is a division of application No. 29/598,471, filed on Mar. 27, 2017, now Pat. No. Des. 868,377.

CLAIM

The ornamental design for an electric dry shaver head, as shown and described.

DESCRIPTION

FIG. 1 is a perspective view of the first embodiment of an electric dry shaver head;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof.

FIG. 8 is a perspective view of the second embodiment of an electric dry shaver head;

FIG. 9 is a front view thereof;

FIG. 10 is a right side view thereof;

FIG. 11 is a rear view thereof;

FIG. 12 is a left side view thereof;

FIG. 13 is a top plan view thereof; and,

FIG. 14 is a bottom view thereof.
